COMPUTING MACHINE

Oscar J. Sundstrand, Rockford, Ill., assignor, by
mesne assignments, to Underwood Elliott
Fisher Company, New York, N. Y., a corpora-
tion of Delaware

Application November 28, 1932, Serial No. 644,627

5 Claims. (Cl. 235—60)

In one of its aspects, the present invention consists of means under the control of or actuated by the paper carriage for throwing out of use one or more of the denominational orders of a printing and computing mechanism.

In another aspect, the invention consists of means controlled or actuated by the paper carriage for adjusting the stop-setting mechanism.

The invention also comprises means for preventing the printing of useless ciphers when whole numbers are being printed.

The invention is herein shown as embodied in a machine for computing and printing according to the English currency system, one denominational order being devoted to pence, two to shillings and the remainder to pounds. Means has been provided whereby the paper carriage is made capable of so adjusting the stop-setting mechanism that the pence and shillings mechanisms are left idle, thus adapting the machine to the printing and/or registration of whole numbers, as, for example, a number to indicate the folio of a ledger account, and rendering possible automatic printing of the folio in the proper column on a ledger sheet under the control of the paper carriage.

In the accompanying drawings:

Figure 1 is a fragmental plan view of one form of machine embodying the features of my invention.

Fig. 2 is a fragmental left-hand side elevation.

Fig. 3 is a fragmental perspective view, looking from the left-hand side of the machine.

Fig. 4 is a vertical section taken approximately in the plane of line 4—4 of Fig. 5.

Fig. 5 is a fragmental plan view.

Fig. 6 is a plan view showing a dog located on the carriage, and the lever actuated by the dog.

Fig. 7 is a perspective view of one form of means to prevent the printing of unnecessary ciphers.

The invention is herein shown as embodied in a machine of the type shown in my Patent No. 1,885,489, granted November 1, 1932, upon improvements in Decimal and non-decimal adding and subtracting machines, but it should be understood that the invention is not limited to machines of that particular character. Reference may be made to said patent for an understanding of features not fully illustrated and described herein.

The machine illustrated in the drawings is adapted to register and print up to 9,999,999 £, 19s., 11d. A single type bar is employed to print the number of pence and one type bar for each

numerical order of shillings and pounds, hence ten type bars are herein provided. The type bars that print the number of pounds and shillings are marked 3, (Fig. 1), the type bar that prints the number of pence being designated 3'. Said bars are arranged compactly side by side.

The means herein shown for limiting the extent to which the type bars may rise and thus to determine which numerals shall be brought to printing position includes a stationary group of 10 stops 42, which may be similar to those fully disclosed in the Sundstrand Patents Nos. 1,198,-487 and 1,583,102. When moved rearwardly from the position shown in Fig. 1, the stops are in the path of movement of devices carried by the type bars and thereby limit the upward movement of said type bars. These devices consist of arms 45 pivoted to the lower portions of the type bars, and stop pins 46 connected to the forward ends of the arms 45. The pins 46 are guided for vertical movement in a slide 47 (Figs. 2 and 5) which is mounted on a stationary guide rod 48 extending transversely of the machine. The guide rod 48 is so positioned with reference to the group of stops 42 that the slide 47 is movable to carry the pins 46 from their normal or initial position at the left-hand side of the group of stops 42 into vertical alignment with the columns of stops.

The means for projecting the stops 42 into the path of the pins 46 comprises numeral keys 49 (Fig. 1) and a series of push pins 50 (Fig. 4) arranged to be projected rearwardly by the keys. The rear ends of the push pins are supported by means including a bracket 51 (Fig. 5) which is pivoted in the machine frame at 52, and is caused to swing toward the right by means of a contractile spring 53. The rear end of the bracket 51 is connected to the slide 47 by means of a stud 54 engaging a fork 55 on said slide. Overlying the bracket 51 is an arm 56 (Figs. 1 and 4) which also is pivoted at 52. Fixed to the rear end of the arm 56 is a post 57 in which the rear portions of the push pins 50 are slidably guided. The arm 56 carries a bracket 58 that slidably supports the rear end of the bracket 51. The bracket 51 and the arm 56 swing as a unit when amounts are being set up by means of the keyboard, but when work in decimals or whole numbers is being done they occupy different relative positions than when work in English currency notation is being performed. On the lower side of the arm 56 is a roller stud 59 (Figs. 4 and 5) that may be adjacent to either of two lugs 60 and 61 on the bracket 51. A slide 62 on the bracket 51 is mov-

able along the lug 61 and has a cam surface 63 arranged to act on the roller stud 59. A pin 64 on the slide 62 extends through a slot 65 formed longitudinally of the bracket 51 and through a curved slot 66 in a lever 67 pivoted at one end at 68 in the machine frame. The other end of the lever 67 has a pin-and-slot connection 69 (Fig. 2) with one arm of a bell crank lever 70 pivoted at 71. To the other arm of the bell crank lever 70 is pivoted the stem 72 of a whole number key 73. A contractile spring 74 connected to a pin 74^a on the key stem 72 normally holds the key 73 elevated, with a stop lug 75 in contact with the keyboard plate 76, and also holds the lever 67 in the position shown in Fig. 5. When the lever 67 is in the position just referred to, the slot 66 is concentric with the axis 52 and hence does not affect the slide 62 as the bracket 51 and the arm 56 swing on said axis. When the key 73 is depressed the lever 67 is swung forwardly (see Fig. 1), carrying with it the slide 62. To insure that the lever 67 shall stay in such position a detent 76^a (Fig. 2) is pivoted at 77 and urged against a pin 78 on the bell crank lever 70 by a contractile spring 79. Said detent has a notch 80 to receive the pin 78. In the return stroke of the handle 27 (i. e. the latter half of the cycle of operations of the machine, the detent 76^a is disengaged from the bell crank 70 through contact of a pin 81 (Fig. 2) with the lower end of the detent, said pin being set in the bar 82 that restores the bracket 51 and the slide 47 to initial position (see the Sundstrand Patent No. 1,198,487). In the return or leftward movement of the bracket 51, the lug 60 (Fig. 5), engages the roller 59 on the arm 56 and carries the latter back to initial position, as in Fig. 5.

It may be stated that in both positions of the arm 67 the slot 66 is substantially concentric with the pivot 52.

Depression of the whole number key 73 withdraws the cam surface 63 from between the roller stud 59 on the arm 56 and the lug 61 on the bracket 51, thereby allowing the spring 53 to swing the bracket 51 toward the right until the lug 61 stops against the roller stud 59, the arm 56 that carries said roller stud being meanwhile held against movement to the right by the escapement bar 83 (Fig. 1). Such movement of the bracket 51 causes movement of the slide 47 toward the right, whereby the pins 46 for the pence, units-shillings and tens-shillings type bars are carried to the right of any stops 42 that might be subsequently set by means of the numeral 55 keys. Any such stops will therefore act to position only the type bars and racks that register and record whole numbers.

The before mentioned Patent No. 1,885,489 discloses means to prevent the pence, units-shillings and tens-shillings type bars from rising above the cipher-printing position when whole numbers are being registered or printed. Such means or its equivalent is employed in connection with the present invention, 83^a being the detent bail 65 connected to the lever 70 by a link 83^b.

Said Patent No. 1,885,489 also discloses means whereby, when an amount consisting of a whole number is set up, with the key 73 depressed, the "0" key need not be operated for the shillings and pence orders, the ciphers for those columns being automatically printed. The present invention contemplates, as one of the uses of whole numbers, the printing of folios; but it will be seen that the printing of ciphers in the pence and shillings orders would be unnecessary and undesirable

when folios are being printed. I therefore provide means whereby such undesirable printing of ciphers is eliminated. This means cooperates with the spacing-stroke-enforcing means. The latter may be identical with or substantially similar to that fully disclosed in my Patent No. 1,583,102. Using the reference numbers employed in that patent, 300 (Figs. 2 and 4) is a plate pivoted at 301 and held in either of its two positions by a detent 306. Said detent is pivoted at 306^a 10 and is held in engagement with the plate 300 by a spring 307. The plate 300 is in its forward position, as shown in Fig. 2, after a blank or spacing cycle has been performed preparatory to the taking of a total. It is swung into its rear position when a digit is set up in the keyboard, and remains in that position until after the first half of a blank or spacing cycle has been performed. It will be noted in Fig. 2 that the detent 306 occupies a lower position when the plate 300 is in 20 its rear position than when said plate is in its forward or total-taking position.

The printing hammers 180 (Fig. 7) for the pence, units-shillings and tens-shillings orders are arranged to be held out of operation by a 25 detent 84 which is pivoted to swing up and down on two screws 85. A spring 86 tends to lower the detent 84 into position to block the rearward movement of the three hammers just referred to. Pivoted to the detent 84 is a link 87 30 which is guided on a stud 88. The link 87 has an angular arm 89 that rests on the detent 306 and overlies the pin 74^a on the stem 72 of the whole number key 73.

When the whole number key 73 is depressed 35 and the plate 300 is in its rear position, the detent 84 is in its lower position, and thus prevents the printing of three ciphers following the digits representing, say, a folio.

When the plate 300 is in its forward position, 40 as it is after a blank cycle preparatory to the taking of a total, the detent 84 is held in its upper or ineffective position by the detent 306, thus enabling the printing of ciphers as required in the printing of the total amount accumulated in 45 the totalizer or register. It will be seen that the printing of ciphers in total-taking is permitted even though the whole number key has been left latched down, as described in said Patent No. 1,885,489.

Means is provided whereby the functions performed by the manually-operable key 73 may also be performed by the paper carriage. The latter, which may be of any desired construction, as, for example, that disclosed in my application 55 Serial No. 118,628, filed June 26, 1926, is indicated herein at 90 (Fig. 3). It is supported in any preferred way for movement transversely of the machine. Attached to the carriage is a bar 91 extending parallel with the direction of travel. 60 A bracket 92 is secured to the bar 91 in a manner to permit of adjustment to any point along the bar, a clamping screw 93 serving to hold the bracket in the desired location. On the bracket 92 is mounted a cam or dog 94 in such a way 65 as to be effective only during the leftward or working stroke of the carriage. Herein the dog 94 is shown as pivoted at 95 to the bracket 92, a contractile spring 96 normally holding the dog against a stop pin 97 on the bracket. The leftward edge of the dog 94 is beveled to engage a roller 98 carried on the upper end of a lever 99 pivoted in the machine frame at 100. The lower end of the lever 99 is pivoted to one arm of a lever 101 pivoted at 102 in the machine frame.

The other arm of the lever 101 is pivoted to the rear end of a link 103, the forward end of the link being pivoted to one arm of a lever 104 pivoted at 105 in the machine frame. The other arm of the lever 104 lies just behind the lever 67. A spring 106 connected to the lever 104 normally holds the lever 104 away from the lever 67 and holds the roller 98 in the path of the dog 94. The action of the spring 106 is limited by a stop 107 located on the machine frame in position to be engaged by a pin 108 on the lever 99.

The dog 94 may be set on the carriage rod 91 in a position corresponding, for example, to a column on the work sheet in which some whole number, as, for instance, the folio, is to be printed. As the carriage reaches such columnar position and comes to rest there, the dog 94 cams back the roller 98 against the tension of the spring 106, thereby forcing the lever 67 into its forward position. Such movement of the lever 67, as before explained, allows the bracket 51 to swing to the right under the tension of the spring 53, the arm 56 being meanwhile held in the initial position by the escapement bar 83. This movement of the bracket 51 carries the slide 47 to the right far enough to place the stop pins 46 that are associated with the pence, units-shillings and tens-shillings type bars out of position to engage any stops 42 that may be subsequently set by the push pins 50. It will be noted in Fig. 1 that the fourth stop pin 46 from the right (which pin is associated with the units pounds type bar) will move into position directly below a stop 42 in the column of stops farthest to the left after such stop 42 has been set by the corresponding push pin 50 and the arm 56 and bracket 51 have been swung one step to the right by the spring 53. Thus the operator may operate such of the numeral keys 49 representing the digits from "0" to "9", inclusive, as are necessary to set up a whole number representing a folio, when the carriage reaches the columnar position wherein the folio is to be printed on the ledger sheet or other work-piece, without the necessity of manually depressing the whole

number key 73. The setting up of the folio on the keyboard results in the movement of the plate 300 to its rear position, if it was not already there, thus lowering the hammer detent 84 into position to prevent three useless ciphers from 5 being printed at the right of the folio.

I claim as my invention:

1. A computing machine having, in combination, a series of reciprocatory type bars, a corresponding series of printing hammers, and means 10 for automatically limiting movement of one of the type bars and disabling the corresponding hammer.

2. A computing machine having, in combination, a series of reciprocatory type bars, a corresponding series of printing hammers, a laterally movable paper carriage, and means actuated by the paper carriage for limiting movement of one of the type bars and disabling the corresponding hammer. 20

3. A computing machine having, in combination, a series of hammers, a blank-cycle-enforcing mechanism, and means sensitive to the condition of said mechanism for disabling one of the hammers. 25

4. A computing machine having, in combination, stop-setting mechanism, a whole number key and connections for adjusting said mechanism, a series of hammers, a blank-cycle-enforcing mechanism, and means sensitive to the position of the last-mentioned mechanism and said key for disabling one of the hammers. 30

5. A computing machine having, in combination, stop-setting mechanism, a whole number key and connections for adjusting said mechanism, a series of hammers, a blank-cycle-enforcing mechanism having an item-entering and a total-taking position, and means for disabling one of the hammers when said blank-cycle-enforcing mechanism is in its item-entering position and the 40 said key is in its effective position, said hammer-disabling means being ineffective when the blank-cycle-enforcing mechanism is in its total-taking position or said key is in its ineffective position.

OSCAR J SUNDSTRAND. 45
